Irving M. Hoglin, Boulder, Colo.

Application June 19, 1944, Serial No. 114,082

Term of patent 7 years

(Cl. D71—1)

To all whom it may concern:

Be it known that I, Irving M. Hoglin, a citizen of the United States of America, residing at Boulder, in the county of Boulder and State of Colorado, have invented a new, original, and ornamental Design for a Transparent Hood for Aircraft or Similar Article, of which the following is a specification, reference being had to the accompanying drawing, forming a part thereof.

In the drawing:

Figure 1 is a side elevational view of a transparent hood for aircraft or similar article, showing my new design,

Figure 2 is a top plan view of the same, and
Figure 3 is a front elevational view of the same.
I claim:

The ornamental design for a transparent hood for aircraft or similar article, as shown.

IRVING M. HOGLIN.
